135,914

DESIGN FOR A RUG OR SIMILAR ARTICLE

Max Sadinoff, Bronx, N. Y.

Application September 19, 1942, Serial No. 108,279

Term of patent 14 years

To all whom it may concern:

Be it known that I, Max Sadinoff, a citizen of the United States of America, residing in the Bronx, county of Bronx, and State of New York, have invented a new, original, and ornamental Design for a Rug or Similar Article, of which the following is a specification, reference being had to the accompanying drawing, forming a part thereof.

In the drawing:

Figure 1 is a plan view of a rug showing my new design.

Figure 2 is a sectional view taken along the line 2—2 of Figure 1 drawn to an enlarged scale, showing the successive rows of yarn braid of which the rug is made as applied to the backing of the rug.

Figure 3 is a sectional view taken along the

line 3—3 of Fig. 1 and Fig. 2, drawn to an enlarged scale showing a portion of the yarn braid as applied to the backing with one half of the braid cut away to show the alternating sections of cut and uncut yarn forming the yarn braid of which the rug is made.

The characteristic feature of my design for a rug resides in the combination of alternating cut and uncut groups of yarn loops or tufts of substantial areas arranged in regular succession around the circumference of the rug, with similar areas of cut and uncut groups of yarn loops or tufts arranged promiscuously over the remaining portion of the rug as shown.

I claim:

The ornamental design for a rug or similar article, as shown and described.

MAX SADINOFF.
